UNITED STATES PATENT OFFICE.

FRANKLIN L. LANE AND FRANK R. WEAVER, OF BELOIT, WISCONSIN, ASSIGNORS TO THE BERLIN MACHINE WORKS, OF BELOIT, WISCONSIN, A CORPORATION OF WISCONSIN.

PLANER AND MATCHER.

1,183,013.

Specification of Letters Patent. Patented May 16, 1916.

Application filed January 25, 1915. Serial No. 4,176.

To all whom it may concern:

Be it known that we, FRANKLIN L. LANE and FRANK R. WEAVER, citizens of the United States, residing at Beloit, in the county of Rock and State of Wisconsin, have invented certain new and useful Improvements in Planers and Matchers, of which the following is a specification.

The invention relates to a planing, matching and finishing machine for acting upon lumber or other rough material to the end that in one passage through the machine the same shall be smooth finished on all its surfaces and also tongued, grooved, hollow-backed or otherwise prepared for use as ceiling, flooring and the like.

Among the features of construction characterizing the invention are improved means providing for the easy and accurate adjustment of the operating parts within a wide range to adapt the same to the requirements of the work in hand; also improvements in the construction and mounting of the working parts whereby to effect compactness, elasticity in operation and capacity for performing superior work; also other improvements in construction and operation which will hereinafter be made apparent.

In order that the invention may be readily understood by those skilled in the art, a preferred embodiment of the same in a wood working machine is set forth in the accompanying drawings and in the description based thereon. As, however, the invention is susceptible of embodiment in other and varied constructional forms dependent upon the material and the nature of the work to be performed, the drawing and description are to be taken in an illustrative and not in an unnecessarily limiting sense.

In the drawings Figure 1 is a top plan view of a wood working machine embodying the invention; Fig. 2 is a side elevation of the same; Fig. 3 is a vertical longitudinal section on the line 3—3 of Fig. 1; Figs. 4, 5, 6 and 7 are vertical transverse sections taken on corresponding lines indicated in Figs. 1 and 2; Fig. 8 is a similar section taken on the line 8—8 of Fig. 2; Fig. 9 is a horizontal fragmentary section taken on the line 9—9 of Fig. 2; Fig. 10 is a vertical transverse section taken on the line 10—10 of Fig. 1; Fig. 11 is a front elevation of the main cutter head; Fig. 12 is an edge elevation of the

same; Fig. 13 is a section through the cutter head on the line 13—13 of Fig. 11; Fig. 14 is a detail view in perspective of one of the knife adjusting blocks; and Fig. 15 is an edge elevation of a modified form of cutter head.

Referring to the drawings more in detail, the machine is illustrated as comprising a frame 21 forming a support for the mounting of the various working parts of the machine in operative relation to which the material is adapted to be passed lengthwise of the machine entering at the right hand end as illustrated in Figs. 1 and 2 and emerging in a finished condition from the left hand end as viewed in said figures. The material is fed into and through the machine by means of a series of adjustably fixed and yielding feed rollers arranged in pairs. Of the first pair the fixed roller is indicated at 22 and the yielding roller at 23, the former having a smooth surface and the latter a roughened or toothed surface, the succeeding pairs of rollers 24, 25, 26, 27, 28, and 29 have smooth surfaces on both the fixed and yielding members of each pair.

The feed rollers are driven in the following manner: Referring particularly to Figs. 1, to 4, the main shaft 32 driven by the pulley 33 has mounted thereon a drive pulley 34 from which the belt 35 passes around the driven pulley 36 upon the shaft 37. This shaft 37 has mounted thereon concentric of the pulley 36 a miter gear 38 which meshes with a larger miter gear 39 fixed upon the counter shaft 40 extending lengthwise of the machine frame and serving to transmit power to the several feed rolls. Upon the counter shaft 40 is mounted a bevel pinion 41 in mesh with the bevel pinion 42 fixed upon the vertical shaft 43 which carries pinions 44 and 45. Parallel to the vertical shaft 43 is another vertical shaft 46 carrying at its lower end a pinion 47 in mesh with the pinion 44 driven thereby. The upper end of the shaft 46 has mounted thereon the fixed feed roller 22. Likewise arranged parallel to the shaft 43 at an angle of 90° from the shaft 46 is a vertical shaft 48 carrying the pinion 49 in mesh with the pinion 45. The upper end of the shaft 48 serves as a pivot for the swinging bracket 50 upon which is mounted the yielding feed roll 23. Arranged parallel to the vertical shaft 43,

46, and 48 and immediately behind the shaft 46, as seen in Fig. 3, and behind the shaft 48, as seen in Fig. 4, is another vertical shaft 51 carrying a pinion 52 in mesh with and driven by the pinion 49, the shaft 51 carrying the yielding feed roll 23. By this means the feed rolls 22 and 23 are driven in opposite directions so as to feed the material therebetween and at the same time provision is made whereby the roll 23 may yield in an arcuate path about its pivot 48 without interfering in the driving thereof. At the opposite end of the counter shaft 40 is a bevel pinion 53 in mesh with a bevel pinion 54 carried by the vertical shaft 55 which has fixed thereon pinions 56 and 57, the former in mesh with the pinion 58 carried by the shaft 59 which has mounted thereon the fixed feed roll 28 at the exit end of the machine. The yielding feed roll 29 of this pair is driven from the pinion 57 by means of other pinions and shafts arranged in substantially the same relation as that described for the driving of the yielding feed roll 23.

At an intermediate position the counter shaft 40 carries a bevel pinion 30 in mesh with a similar pinion 31 mounted upon the shaft 60 carrying pinions 61 and 62, the former in mesh with the pinion 63 on the shaft 64 of the fixed feed roll 26. The pinion 62 is in mesh with a pinion 65 by means of which its motion is transmitted to the pinion 66 on the shaft 67 which carries a pinion 68 in mesh with the pinion 69 on the shaft 70 of the fixed feed roll 24. The yielding feed rolls 25 and 27 are driven indirectly from the pinions 66 and 62 by means of interposed pinions and shafts arranged in the manner described with reference to the driving of the yielding feed roll 23. The shafts 46 and 70 of the fixed feed rolls 22 and 24 are not journaled directly in the frame 21 but in a bracket 71 which is adjustable on said frame so as to provide for a slight adjustment of the feed rolls with reference to said frame, the adjustment of the bracket 71 being permitted by the working of the bolts 72 in the slots 73 of a sliding plate 74 and effected by the adjusting nuts 75 and set screws 76. The sliding plate 74 is in turn adjustable on the frame 21 by means of links 77 having threaded engagement with the standards 78 and having at their opposite ends a connection by means of the eccentric straps 79 with the eccentrics 80 fixed on the shaft 81 which shaft is adapted to be rotated from its squared end 82 in any suitable manner as by a wrench or hand wheel and to be locked in an adjusted position by means of the clamping nut 83, while additional provision is made by means of the lever nuts 84 for clamping the plate 74 in adjusted relation to the machine frame 21. This sliding plate 74 has along its extreme edge an upturned flanged

portion 85, the outer surface of which forms a guide rail for the material entering the machine. Ordinarily the guiding surface of the rail 85 would be substantially flush with the adjustably fixed feed rolls 22 and 24 although capable of slight adjustment relative to the feed rolls by means of the adjusting nuts 75 and set screws 76. When once brought into relative adjustment the guide rail and feed rolls are adjusted in unison by means of the shaft 81 and the links 77.

The following provision is made for the automatic yielding and the manual quick release of the yielding member of each pair of feed rolls, the description as applied to the first pair being also applicable to each of the other pairs: Having particular reference to Fig. 9 it will be observed that the feed roll shaft 51 and its gears 49 and 52 are inclosed within a housing 86 adapted to swing about the shaft 48 as a pivot. The housing 86 is provided with a boss 87 serving as a bearing for a pivot 88 by means of which a lever 89 is fulcrumed to the housing. This lever 89 is also fulcrumed at 90 in a bearing block 91 threaded upon the spindle 92 having a squared outer end 93 and guided within an arm 94 carried by the boxing of the shaft 46 of the fixed feed roll. The spindle 92 extends beyond this guiding bearing and has enveloping the same a spring 95 bearing at one end against the arm 94 and at the opposite end against the washer 96 positioned upon the end of the spindle by means of the nuts 97. It will be observed, that, having reference to Fig. 9, the spindle 92 serves as a link connecting the lever 89 with the arm 94 and that in the normal position of the lever 89, here represented, this link lies slightly to the right of the fulcrum 88, the effect being to hold the lever in its normal closed position. If the lever 89 be drawn outwardly toward the observer the first result is to swing the outer end of the link spindle to the left and thereafter the pivot 88 and with it the free end of the housing and also the shaft 51 with the yielding feed roll are swung outwardly about the pivot 90 whereby the space between the feed rolls 22 and 23 is increased and the engagement of the rolls upon a piece of material therebetween is released. By means of the levers 89 it will thus be seen that the material in the machine may be quickly released from engagement between any pair of feed rolls for withdrawal or adjustment.

Next to the first set of feed rolls 22 and 23 is suitably mounted a vertical shaft 98 carrying a drive pulley 99 and having fixed upon its upper end a hollow backed cutter head 100, fitted with knives 101 adapted to finish one side of the material and to hollow back the same by means of the cutter part 102.

102. The shape of these knives and the nature of the work to be performed is not a material feature of the invention as the knives of this cutter head may be changed 5 to accord with the finish desired to be given to that face of the material indicated at 103, in Fig. 5, in the position to be operated upon. The cutter shaft 98 has its bearing within a boxing 104 provided with a lateral 10 extension 105 which is transversely apertured for the reception of a fixed shaft 106 extending transversely of the machine frame through guiding brackets 107 within which it is slidable. Also rotatably mounted but 15 without longitudinal movement in the boxing 104 is an adjusting spindle 108 threaded within a boss 109 of the machine frame and having a squared end 108^a by means of which spindle the boxing 104 and with it 20 the cutter head and shaft are adjusted toward and from the machine frame causing the fixed shaft 106 to slide within its guiding brackets 107. A set screw 110 is provided for gaging the adjustment of the cutter head 25 and the parts are firmly clamped in adjusted position by means of blocks 111 guided for vertical movement within the bosses 112 of the brackets 107 upon screw spindles 113 threaded in the machine frame at 114 and 30 provided with operating handles 115. The clamping blocks 111 have a portion hollowed out, as indicated at 116 to fit the surface of the shaft 106 so that when the spindles 113 are rotated the blocks 111 are caused 35 to engage and firmly clamp the shaft 116 so as to maintain the shaft 98 and the cutter head 100 in adjusted position.

The cutter head 100 is inclosed within a housing 117 having an open side 118 for the 40 attachment of an exhaust device to carry off shavings and the like, the housing being pivoted eccentric to the shaft 98 for swinging movement in order to give access to the cutter head. The swinging housing is 45 latched and released in the manner following: A spring pressed bolt 119 is vertically mounted within the housing, the lower end projecting at 120 and the upper end provided with a handle 121 by means of which 50 it may be lifted in opposition to its spring 122. A keeper rod 123 is horizontally mounted within a bracket 124 carried by the non-rotatable shaft 106 and equipped with a spring 125 bearing at one end against 55 said bracket and at the other end against the washer 126 and the nut 127. The outer end of the keeper rod is provided with an aperture for the reception of the lower end 120 of the bolt and has a downturned terminal 60 portion 128 up which the end of the bolt is adapted to ride before reaching the recess. The keeper rod also has a rearwardly facing shoulder portion 129 adapted to be engaged by the nose 130 of the latch lever 65 131. The housing 117 has a lip portion 117^a which acts as a chip breaker and is held 70 yieldingly in contact with the stock passing through the machine by means of the spring 125. It will be observed that as the cutter and housing are adjusted toward and from 75 the stock by the sliding of the shaft 106 the action of the spring 125 on the chip breaker would vary were it not that the bracket carrying the rod 123 and spring 125 is in turn carried by the shaft 106, whereby 80 the tension of the spring remains unchanged under various adjustments of the cutter head. To release the housing 117 the bolt 119 is retracted out of engagement with the keeper by means of its handle 121 and may 85 then be swung to the open position. In closing, the lower end of the bolt rides up the inclined end of the keeper rod and snaps into the recess. This operation would ensue without difficulty were it not that the spring 85 90 125 acts through the keeper upon the bolt to pull the housing strongly to the right as viewed in Fig. 10. In order to hold the keeper in its extended position against the spring 125 until engaged by the bolt 119 the 95 lever 131 is provided by means of which the operator pushing downward upon the end of the lever bears outwardly against the shoulder 129 of the keeper rod holding the latter in extended position for easy engagement with the bolt until the latter has engaged within the recess. The lever 131 may also be utilized to relieve the tension upon the keeper rod while the bolt is being withdrawn in the opening movement. The upward movement of the lever 131 is limited by means of the stop 132 in order that the spring 125 may not be allowed to draw the keeper rod 123 inwardly too far to be engaged by the bolt or to destroy the engagement between the shoulder 129 and the nose 130 of the lever. 100

Beyond the hollow back cutter head is mounted a pair of feed rolls 24 and 25, the yielding member 25 of which is mounted for 110 swinging movement and provided with a quick release lever connection in the same manner as the yielding feed roll 23, previously described. Between the pair of feed rolls 24 and 25 and the next pair of feed rolls 26, 27, which are similarly mounted, is arranged a main finishing cutter head 133 upon the shaft 134 journaled in the bearings 135, 136 at a slight inclination to the horizontal, as most clearly shown in Fig. 6. The 115 cutter head 133 has a convex or beveled front face, the inclination to each other of those portions of the face on opposite sides of the center being slight and of such extent that when mounted with the shaft 134 at a 120 slight inclination to the horizontal the lower portion of the face of the cutter head will occupy a vertical position, or in a plane parallel to the plane of travel of the stock 125 through the machine while the upper portion 130

tion of the face will lie in a plane at an angle to the vertical and at an angle to the plane of the travel of the stock.

Within the cutter head are mounted a plurality of knives 137 with their cutting edges conforming to the bevel face of the head and substantially flush with the said front face. These knives are mounted within slots of the cutter head in conjunction with gibs 138 having offset heads 139 by means of which their position within the slots is fixed with their outer ends adjacent the cutting edges of the knives where they act as chip-breakers. The knives 137 are positioned and firmly held within the slots by means of blocks 140 of a general cylindrical shape but having a bevel face 141. The blocks are slidably mounted within cylindrical recesses 142 the axes of which are substantially parallel to the axis of the cutter head and therefore at an inclination to the knife slots which are at an angle to the axis of the cutter head the inclined face 141 of the block being substantially parallel to the slot and consequently adapted to bear against the flat face of the gib. The rear end of each block 140 is borne upon by a set screw 143 threaded in the cutter head and squared at 144 for engagement by a suitable tool. For convenience in manufacture the knife slots are milled and extend outwardly to a periphery of the cutter head and a rim 145 is thereafter placed about the cutter head inclosing the ends of the slot, being held in place by means of the screws 146.

The front face of the cutter head where the knives project is provided with grooves 147, that portion of the groove in front of the knife edge having a greater capacity at its outer end, such increase of capacity being attained, as illustrated, by forming said groove of increasing width toward its outer end although the same result may be attained by increasing the depth of the groove toward the outer end, the object being in both cases to provide a clearance channel for the chips by which they are discharged radially.

The object in beveling the operative face of the cutter and mounting its shaft at such an inclination that those knives which are operating upon the stock shall have their cutting edges substantially parallel to the plane of travel of the stock while the opposite knives shall be inclined to such plane, is that the knives shall gradually enter the material and gradually leave the same with the grain of the wool and effect a drawing cut throughout whereby knife marks are entirely avoided and an absolutely smooth finish imparted to the work.

It will be noted that the front face of the cutter head between the knives is substantially flush with the cutting edges of the knives themselves, providing for a projec-

tion of the knives merely sufficient to make a thin cut. The object of this provision is that the material in its passage through the machine shall be supported by the face of the cutter head. This is of great importance particularly where a large cutter head is employed and where warped stock is being treated. Otherwise the material, being unsupported, could spring toward the cutter head and the depth of the cut would be non-uniform.

The cutter head shaft 134 is provided at its rear end with an end thrust bearing 148 adjustable by means of a hand wheel 149 while the forward end of said shaft is provided with an end thrust bearing 150 which is yielding and under control of a compression spring 151, the tension of which spring is adjustable to provide for greater or less resistance. The cutter head 133 is inclosed within a housing 152 open at its upper side at 153 for communication with an exhaust device and hinged at 154 so as to swing in a vertical plane. To the free edge of the housing on that side opposite its pivot 154 is attached a shoe 155 vertically adjustable with reference to the housing by means of bolts 156 engaging within slots 157. The shoe 155 rests upon the upper edge of the stock and under the weight of the housing holds the stock firmly down upon the bed while being operated upon by knives of the cutter head. In order that the lower face of the shoe shall at all times be parallel to and rest throughout its length upon the upper edge of the stock this vertical adjustment is provided. If the shoe were fixed in its relation to the housing the parallel relation of its lower edge to the horizontal would be disturbed when stock of different widths were inserted and the housing thereby lifted or lowered about its pivot. As here arranged the position of the housing is always the same and the shoe is raised or lowered vertically and the horizontal relation of its lower edge maintained. Farther along and between the pairs of feed rolls 26, 27, and 28, 29 is arranged a pair of coöperating cutter heads one above the other and adapted to act upon the upper and lower edges respectively of the stock to finish the same or provide a tongue and groove where flooring is being made. These cutter heads and their housing are substantially the same, differing only in the knives with which they are provided.

The tongue cutter head 158 is fixed upon a shaft 159 carrying a pulley 160 and provided at its forward end with an adjustable end thrust bearing 161 and at its rear end with a yielding spring pressed end thrust bearing 162. The groove cutter head 163 is likewise fixed upon a shaft 164 carrying a pulley 165 and provided at its front end with an adjustable end thrust bearing 166.

and at its rear end with a yielding end 5 thrust bearing contained within a housing 167. The stock in its passage between the tongue and groove cutter heads is held firmly against the gage guides 168 and 169 by means of a pressure roll 170 which is mounted in a bearing bracket 171 forming a housing and hinged at 172, the bracket and with it the roll being pressed inwardly 10 by means of the spring 173 mounted upon the rod 174 and engaging the arm 175 of said bracket.

Provision is made for the adjustment of the tongue and groove cutter heads toward 15 and from each other to accommodate stock of different widths in the manner following: The cutter head shafts 159 and 164 are journaled within bearing boxes 176 and 177 respectively, mounted for vertical adjustment 20 within guides 178 and 179 of the machine frame as is most clearly shown in Figs. 7 and 8. The bearing boxes 176 are engaged by a pair of screw spindles 180 connected at their upper end by means of a cross shaft 25 181 and the bevel gears 182 and 183. One of the bevel gears 182 being in turn in mesh with a bevel gear 184 carried by a shaft 185 and provided with a hand wheel 186. The bearing boxes 177 are engaged by a pair of 30 screw spindles 187 each provided with a worm wheel 188, each of which is in mesh with a worm 189 on the shaft 190 provided at its front end with a squared portion 191. By turning the hand wheel 186 and the 35 worm shaft 190 the respective bearing boxes 176 and 177 will be moved upwardly or downwardly so as to bring the knives of the tongue and groove cutters closer together or farther apart. In order to provide for 40 the clamping of the bearing boxes in adjusted position and to release the same for adjustment when desired a cam rod 192 is provided, equipped with an operating handle 193, said cam rod bearing against a wear 45 plate on one of the guides 178 and encircled by bearing knuckles of strut rods 194 extending across the intervening space and having an adjustable bearing by means of the nuts 195 upon the opposite guide 179. 50 The guide 179 is split at 196 (Fig. 8) so as to permit the same to yield slightly and thus providing for the clamping and releasing of the coöperating portions of the bearing boxes 176. 55 The several cutter heads are driven from the one shaft 32 in the manner following: The pulley 99 of the hollow back cutter head is driven by means of the belt 197 from the pulley 198, the belt traversing the belt tightener pulley 199 which is acted upon by the weight 200. The main surfacing cutter head 133 and the tongue and groove cutter heads 158 and 163 are driven from the pulley 201 by means of the belt 202 which passes 60 from the upper side of said pulley over

the pulley 160, under the pulley 165, around the pulley 203 of the shaft 134 and back to the said drive pulley 201. The driving of the feed rolls and consequently the passage of the material through the machine is controlled by a hand lever 204, fulcrumed at 205 and connected by means of the arm 206 with a link 207 which in turn is pivoted to an arm 208 fixed upon the rock shaft 209, which shaft carries oppositely arranged belt 70 tensioning pulleys 210 and 211 by means of which under the control of the lever 204 the belt 35 is loosened or tightened so as to start and stop the driving of the countershaft 40 and the rotation of the feed rolls. The 80 stock leaving the tongue and groove cutters passes between the feed rolls 28 and 29 and is by them fed from the machine in a finished condition requiring no further treatment to fit the same for the reception 85 of a high polish or for use under the most exacting conditions.

In Fig. 15 is shown in edge elevation a slightly modified form of cutter head, the features of difference being that the front 90 face of the head, instead of lying throughout in approximately the rotational plane of the cutting edges of the tools and being provided with special chip-clearance grooves, has at certain points intermediate the knives 95 projecting bosses 212 the front slightly beveled faces of which extend to a plane substantially flush with the knife edges and form a side support for the stock, the depressed face of the head between the bosses 100 and knives serving the same chip clearance function as the grooves 147 in the former case.

We claim:

1. In a machine of the character described, the combination of a series of feed 105 rolls arranged in pairs, a guide rail having its face substantially tangent to that of certain of the rolls, and means to adjust the position of the guide rail independently of the feed rolls and together therewith. 110

2. In a machine of the character described, the combination of a series of feed rolls arranged in pairs, one member adjustably fixed in position and the other 115 yieldingly mounted, a guide rail having its face substantially tangent to that of the fixed rolls, and means to adjust the position of the guide rail independently of the fixed rolls and together therewith.

3. In a machine of the character described, the combination of a series of feed rolls arranged in pairs, one member adjustably fixed in position and the other 120 yieldingly mounted, a guide rail having its face substantially tangent to that of the fixed rolls, a frame carrying the guide rail, a rotatable adjusting shaft, links connecting the shaft and frame whereby to adjust the 125 guide rail, and means to lock the frame in adjusted position. 130

4. In a machine of the character described, the combination of a series of feed rolls arranged in pairs, one member adjustably fixed in position and the other 5 yieldingly mounted, a guide rail having its face substantially tangent to that of the fixed rolls, a frame carrying the guide rail, a rotatable adjusting shaft, links connecting the shaft and frame whereby to adjust the 10 guide rail, means to lock the frame in adjusted position, and an adjustable connection between the fixed feed rolls and frame whereby to effect relative adjustment of the rolls and the guide rail.
- 15 5. In a machine of the character described, the combination of a series of feed rolls arranged in pairs, one member adjustably fixed in position and the other yieldingly mounted, a guide rail having its face substantially tangent to that of the fixed rolls, a frame carrying the guide rail, a rotatable adjusting shaft, links connecting the shaft and frame whereby to adjust the guide rail, a second frame carrying a fixed feed roll, 20 and means for adjustably connecting the two frames together.
- 25 6. In a machine of the character described, the combination of a series of feed rolls arranged in pairs, one roll of each pair 30 journaled in an eccentrically arranged frame to swing in a plane perpendicular to its axis toward and from its companion roll, a release lever fulcrumed to the frame, and a link connecting the lever at a point near its 35 fulcrum with a suitable support, the link lying at one side of the fulcrum in the normal position of the lever and arranged to swing to the other side of the fulcrum in the released position whereby to serve as a 40 yielding lock for the lever and frame.
- 45 7. In a machine of the character described, the combination of a series of feed rolls arranged in pairs, one roll of each pair journaled in an eccentrically arranged frame to 50 swing in a plane perpendicular to its axis toward and from its companion roll, a release lever fulcrumed to the frame, and a spring pressed link connecting the lever at a point near its fulcrum with the fixed support 55 on the opposite side thereof, the link lying at one side of the fulcrum in the normal position of the lever and arranged to swing to the other side of the fulcrum in the released position whereby to serve as a yielding lock for the lever and frame.
- 60 8. In a machine of the character described, the combination of a series of feed rolls arranged in pairs, one roll of each pair journaled in an eccentrically arranged frame to 65 swing in a plane perpendicular to its axis toward and from its companion roll, a release lever fulcrumed to the frame, an apertured bearing support, a link bar traversing the aperture, a spring mounted on one end of the link bar and bearing against the support and an enlarged end of the bar, the other end of the link connected to the lever at a point near its fulcrum, the link lying at one side of the fulcrum in the normal position of the lever and arranged to swing to the other side of the fulcrum in the released position whereby to serve as a yielding lock for the lever and frame.
- 75 9. In a machine of the character described, the combination of a series of feed rolls arranged in pairs, intermeshing pinions for driving one roll of each pair, said roll journaled in a frame hinged upon a pivot concentric with the axis of its driving pinion to swing in a plane perpendicular to its axis 80 in an arc concentric with its driving pinion, a release lever fulcrumed to the frame, and a link connecting the lever at a point near its fulcrum with a suitable support, the link lying at one side of the fulcrum in the normal position of the lever and arranged to swing to the other side of the fulcrum in the released position whereby to serve as a yielding lock for the lever and frame.
- 85 10. In a machine of the character described, the combination of a series of feed rolls arranged in pairs, intermeshing pinions for driving one roll of each pair, said roll journaled in a frame hinged upon a pivot concentric with the axis of its driving pinion to swing in a plane perpendicular to its axis 90 in an arc concentric with its driving pinion, a release lever fulcrumed to the frame, an apertured bearing support, a link bar traversing the aperture, a spring mounted on one end of the link bar and bearing against the support and an enlarged end of the bar, the other end of the link connected to the lever at a point near its fulcrum, the link lying at one side of the fulcrum in the normal position of the lever and arranged to swing to the other side of the fulcrum in the released position whereby to serve as a yielding lock for the lever and frame.
- 95 11. In a machine of the character described, the combination of a pair of feed rolls arranged in opposition one to the other, and means for driving said rolls in opposite directions in order to feed the material therethrough, said driving means comprising pinions mounted upon each of the feed roll axles, a drive shaft carrying two pinions, a driven shaft carrying a single pinion in mesh with the pinion of one of the feed roll axles and also in mesh with one of the pinions upon the drive shaft, the other pinion of the drive shaft being in mesh with the pinion of the other feed roll axle, and means for driving the drive shaft.
- 100 12. In a machine of the character described, the combination of a series of feed rolls arranged in pairs, the rolls of each pair opposed one to the other, and means for driving the rolls of each pair in opposite directions so as to feed the material 105
- 110
- 115

therebetween, said driving means comprising a pinion on each of the feed roll axles, a pair of drive shafts each carrying two pinions, an idler pinion connecting two of the 5 pinions of the drive shafts, a pair of driven shafts each carrying a single pinion in mesh with the pinion of one of the feed roll axles of each pair, and also in mesh with one of the pinions upon one of the drive shafts, the 10 other pinion of each drive shaft in mesh with the pinion of the other feed roll axle of that pair, and means to drive one of the drive shafts.

13. In a machine of the character described, the combination of a work support, a machine element arranged to act on the work in opposition to the support, a supporting frame for said element movable toward and from the work support, a release 15 lever fulcrumed on the frame, a spring pressed link connecting the lever at a point near its fulcrum with a suitable support, the link lying at one side of the fulcrum in the forward position of the lever and arranged to swing to the other side of the fulcrum in the released position whereby to serve as a quick release lock for the frame and machine element.

14. In a machine of the character described, the combination of a fixed feed roll serving as a work support, a second feed roll arranged to act on the work in opposition to the support, a supporting frame for said second feed roll, said frame arranged 20 to swing toward and from the work support, a release lever fulcrumed on the frame near its free edge, a spring-pressed link connecting the lever at a point near its fulcrum with a suitable support, the link lying at 25 one side of the fulcrum in the normal position of the lever and arranged to swing to the other side of the fulcrum in the released position whereby to serve as a quick release lock for the frame and second feed roll.

45 15. In a machine of the character de-

scribed, the combination of a fixed feed roll serving as a work support, a second feed roll arranged to act on the work in opposition to the support, a supporting frame for said second feed roll, said frame arranged to 50 swing toward and from the work support, a release lever fulcrumed on the frame near its free edge, a spring-pressed link connecting the lever at a point near its fulcrum with a suitable support, the link lying at one 55 side of the fulcrum in the normal position of the lever and arranged to swing to the other side of the fulcrum in the released position whereby to serve as a quick release lock for the frame and second feed roll, 60 means to adjust the tension of the spring acting on the link, and means to adjust the connection of the link to the lever and frame without affecting the spring tension.

16. In a machine of the character described, the combination of a frame, a second frame, a swinging body hinged to the second frame, means to adjust the frames bodily toward and from each other, and a latch mechanism for swinging the body 70 comprising a bolt, a keeper having an aperture adapted to receive the bolt end in the closed position, a bracket moving with the second frame in its adjustment toward and from the first frame, the keeper slidably 75 mounted on the bracket, a spring acting on the keeper and the bracket to retain the keeper yieldingly in retracted position, and a lever arranged to act on the keeper in opposition to the spring.

80 In witness whereof we have hereunto signed our names in the presence of two subscribing witnesses.
